UNITED STATES PATENT OFFICE

112,809

DESIGN FOR A CASTER SUPPORTING
BRACKET OR SIMILAR ARTICLE

Paul M. Fuller, Chicago, Ill., assignor to The
Rudolph Wurlitzer Company, North Tonawanda,
N. Y., a corporation of Ohio

Application January 5, 1938, Serial No. 74,098

Term of patent 7 years

To all whom it may concern:

Be it known, that I, Paul M. Fuller, a citizen of the United States, residing at Chicago, in the county of Cook and State of Illinois, have invented a new, original, and ornamental design for Caster Supporting Bracket or Similar Article, of which the following is a specification, reference being had to the accompanying drawing forming a part thereof.

Figure 1 is a side elevation of the bracket embodying my design. Figure 2 is a front elevation of the same.

I claim:

The ornamental design for a caster supporting bracket or similar article, substantially as shown.

PAUL M. FULLER.
